UNITED STATES PATENT OFFICE.

JOHN A. DAVIS, OF WASHINGTON, DISTRICT OF COLUMBIA.

DESIGN FOR A TURNTABLE FOR TALKING-MACHINES.

58,553.

Specification for Design.

Patented Aug. 2, 1921.

Application filed June 19, 1920. Serial No. 390,264. Term of patent 7 years.

To all whom it may concern:

Be it known that I, JOHN A. DAVIS, a citizen of the United States, whose post-office address is care of the United States Navy, Washington, District of Columbia, have invented a new, original, and ornamental Design for a Turntable for Talking-Machines, of which the following is a specification, reference being had to the accompanying drawing, forming part thereof.

The figure is a perspective view of a turn-

table for talking machines, showing my new design, the design consisting of a turntable having its peripheral edge sloping. In the embodiment of the invention illustrated in the accompanying drawing, the sloping edge is shown as a straight, plain and unornamented bevel.

I claim:

The ornamental design for a turntable for talking machines, as shown and described.

JOHN A. DAVIS.
